UNITED STATES PATENT OFFICE

135,668

DESIGN FOR A POULTRY PICKING MACHINE

Flournoy Corey, Cedar Rapids, and Maurice J. Fletcher, Des Moines, Iowa, assignors to Pickwick Corporation, Cedar Rapids, Iowa, a corporation of Iowa

Application April 13, 1942, Serial No. 106,565

Term of patent 14 years

To all whom it may concern:

Be it known that we, Flournoy Corey, and Maurice J. Fletcher, citizens of the United States, residing at Cedar Rapids, in the county of Linn and State of Iowa, and Des Moines, county of Polk, State of Iowa, respectively, have invented a new, original, and ornamental Design for a Poultry Picking Machine, of which the following is a specification, reference being had to the accompanying drawings, forming part thereof.

Figure 1 is a front perspective view of a poultry picking machine showing our new design and

Figure 2 is a rear perspective view thereof.

We claim:

The ornamental design for a poultry picking machine, as shown.

FLOURNOY COREY.
MAURICE J. FLETCHER.
